NONICING CARBURETOR

George M. Bicknell, St. Louis, Mo., assignor to
 Carter Carburetor Corporation, St. Louis, Mo.,
 a corporation of Delaware

Application June 24, 1943, Serial No. 492,146

1 Claim. (Cl. 261—41)

1

This invention relates to carburetors for internal combustion engines and consists particularly in novel means for delivering metered fuel to the mixture conduit substantially posterior to the throttle valve for idling operation, the idling port being positioned so that the cooling effect of the vaporizing idling fuel is not transmitted readily to the throttle plate and icing of the throttle is thereby retarded or prevented.

In modern carburetors, it is conventional to provide an idling port which is located immediately abreast the edge of the throttle valve when closed so that as the throttle is opened, more of the port is exposed directly to engine suction and, accordingly, the fuel supplied through the port is increased to insure the formation of a combustible mixture with the increasing quantity of air which passes the throttle.

With this location of the idling port, the vaporizing of the idling fuel, particularly, just after starting under low temperature conditions, cools the throttle plate so that ice may form thereon which may clog the port and otherwise undesirably affect the carburetor operation.

If the idling port is located wholly posterior to the throttle, although an adequate mixture may be supplied for dead idling operation, this mixture would become sharply leaner as the throttle is opened because of the decreasing suction applied thereto accompanied by increasing air flow. The result would be that for slightly open positions of the throttle valve, the mixture supplied by the carburetor would be too lean to burn in the engine cylinders.

It is an object of the present invention to provide an idling system which discharges sufficiently beyond the throttle plate to eliminate icing of the throttle as the result of vaporization of the idling fuel and provided with means to increase the supply of idling fuel as the throttle is opened so as to insure the formation of a combustible mixture.

This object and other more detailed objects are attained substantially by the device illustrated in the accompanying drawing in which:

Fig. 1 is a vertical sectional view of a carburetor embodying the invention and showing the throttle in idling position.

Fig. 2 is a similar view but showing the throttle and metering valves in different positions.

The carburetor shown has a downdraft mixture conduit including an air inlet horn 6 at the upper end controlled by a butterfly choke valve 7. The outlet portion 8 of the mixture conduit is flanged as at 9 for attachment to an engine intake mani-

fold (not shown) and is controlled by a butterfly throttle valve 10 mounted on a shaft 11 on which is secured the usual throttle lever (not shown) for connection to the accelerator pedal in the driver's compartment. Adjacent the mixture conduit there is a fuel bowl 12 within which fuel is maintained at a substantially constant level by a float 13 and needle valve mechanism (not shown).

Located in the lower portion of the fuel bowl is the main metering orifice element 15 communicating with main mixture passage 16 and nozzle 17 discharging into the smallest of a series of venturis 18 located in the middle or mixing chamber portion of the conduit. A second metering orifice element 19 is located in the lower portion of bowl 12 and communicates with passages 20 and 21, the latter opening into the mixture conduit through a port 22 located substantially posterior to the throttle plate 12. The idling passage is provided with a restricted air bleed opening 23 and fuel restrictions 24 and 25. Metering orifice 15 is controlled by a metering pin 28, having a lower graduated portion extending through the orifice, and is pinned at its upper end to a lever 29 pivotally supported on top of the fuel bowl. The opposite end of lever 29 is connected by a link 30 to an arm 31 rigid with throttle shaft 11. Orifice element 19 in the idling passage is controlled by a second metering pin 32, having a tapered lower portion extending through the orifice, and is pinned at its upper end to a second lever 33 pivoted above the top of the fuel bowl. The inner end of this lever is connected by a link 34 to throttle arm 31.

In operation, when the throttle plate is in the fully closed position, as in Fig. 1, engine suction is applied to idling port 22 to draw a rich mixture of fuel and air into the engine. At this time little or no air passes the throttle plate so that main nozzle 17 is inoperative and metering pin 32 will be lowered to a position to bring a relatively large portion thereof into the metering orifice so as to provide just sufficient fuel for idling operation. As the throttle is opened slightly, the air flow past the throttle and also past nozzle 17 increases, but is not yet sufficient to draw fuel from the main nozzle. To provide for this increasing air flow, metering pin 32 is lifted by link 34, 33 to bring a smaller portion of the pin into the orifice, thus increasing the effective size thereof and, consequently, the quantity of fuel drawn through the idling system. When the throttle is opened further, toward the position as in Fig. 2, fuel will start to discharge from the

main nozzle and, thereafter, most of the fuel will come from this source and the idling discharge becomes negligible. In the throttle position shown in Fig. 2, main metering rod 28 is lifted to a point to bring the smallest or power step thereon into orifice element 15. During high speed operation, a uniformly shaped portion of pin 32 may be positioned in orifice 19.

The independent idling arrangement, as shown, wherein the idling and main fuel passages communicate with the fuel chamber through separate metering orifices, is particularly advantageous in connection with the non-icing arrangement of the idling fuel port. However, various features of the carburetor as shown are not essential and these may be modified as will occur to those skilled in the art without departing from the spirit of the invention and the exclusive use of all such modifications as come within the scope of the appended claim is contemplated.

I claim:

In a carburetor, a mixture conduit, a choke and

a throttle valve in said conduit, a float controlled fuel chamber, a main fuel passage extending from said fuel chamber and discharging into said mixture conduit through an opening anterior to said throttle, a metering orifice communicating with said main fuel passage, a metering pin controlling said main fuel orifice, an independent idling fuel passage extending from said fuel chamber and discharging into said mixture conduit through a port spaced substantially posterior to said throttle valve when the latter is in its closed position, the spacing of said idling fuel port from said throttle being so arranged that the vaporization of the idling fuel therefrom will take place wholly beyond said throttle valve to avoid icing the same, a metering orifice in said idling passage, a stepped metering pin for said metering orifice, and a connection between said last named metering pin and throttle, whereby the supply of idling fuel will gradually increase with the movement of the throttle toward open position.

GEORGE M. BICKNELL.
